Primary Examiner — Karen S Acker*Assistant Examiner* — Steven B Reinholdt, Jr.(74) *Attorney, Agent, or Firm* — Steven E. Shapiro(57) **CLAIM**

The ornamental design for a funnel, as shown and described.

DESCRIPTION

FIG. 1 is a top, front, left side perspective view of a funnel; FIG. 2 is a rear, bottom, right side perspective view of the funnel;

FIG. 3 is a front plan view of the funnel;

FIG. 4 is a rear plan view of the funnel;

FIG. 5 is a left side plan view of the funnel;

FIG. 6 is a right side plan view of the funnel;

FIG. 7 is a top plan view of the funnel; and,

FIG. 8 is a bottom plan view of the funnel.

The broken lines and the areas within them depict portions of the funnel that form no part of the claim.

1 Claim, 8 Drawing Sheets(56)
